DISPENSING CONTAINER

Champe S. Andrews, North Chattanooga, Tenn.,
assignor to Box Blank Corporation, New York,
N. Y., a corporation of Delaware

Application July 15, 1932, Serial No. 622,653

9 Claims. (Cl. 229—7)

This invention relates to a dispensing container in which absorbent cotton or other merchandise may be packed and fully protected against contamination, exposure and foreign matter and from which it can be conveniently dispensed when material is desired for use.

This application is a continuation in part of my co-pending application Serial No. 580,751, filed December 14, 1931.

10 Absorbent cotton has generally been packed in containers which leave the cotton exposed to the atmosphere and foreign matter, greatly increasing the danger of contamination and infection. Absorbent cotton dispensers heretofore used which do protect the contents to some extent have all been very expensive to make, the cost of the container often being more than the cost of the contents. I have met this problem by providing a dispensing container of paper material which can be made by automatic machinery now in use at a very little cost. The container can be made from a single blank of paper material cut by automatic machinery to the proper shape and then folded and cemented together by a folding and gluing machine.

15 An object of my invention is to provide a container in which material can be packed and shipped and from which the material packed therein can be dispensed in an efficient and attractive manner with full protection to the contents against exposure, contamination or foreign matter at all times.

Another object of my invention is to provide a dispensing container particularly adapted to dispense absorbent cotton which fully protects and safeguards the material contained therein against foreign matter and contamination, which is fully closed when not in use and which can be opened to permit access to the dispensing medium from which the cotton is dispensed when desired for use.

Another object of my invention is to provide a dispensing container which can be made entirely by machine operation, which fully protects the contents at all times, which is sturdy and strong in construction, and which can be made in a variety of attractive designs and patterns.

Other objects of this invention will become apparent as the disclosure proceeds.

50 Although the novel features which are believed to be characteristic of this invention will be particularly pointed out in the claims appended hereto, the invention itself, as to its objects and advantages, and the manner in which it may be carried out, may be better understood

5 by referring to the following description taken in connection with the accompanying drawings forming a part thereof, in which

Fig. 1 shows an extended blank from which the body portion and cover portion of the dispensing container may be formed; 5

Fig. 2 shows an extended blank from which the dispensing medium may be formed;

Fig. 3 shows an extended blank from which the guide device may be formed;

Fig. 4 shows a perspective view of a complete set up container formed from the blanks shown in Figs. 1, 2 and 3;

Fig. 5 shows a vertical cross sectional view through the complete container, illustrating 15 more particularly the construction thereof;

Fig. 6 shows an exploded view of the various parts which form the dispensing container; and

Fig. 7 is a perspective view of the dispensing container and guide device illustrating more 20 particularly the method of packing a ribbon or rope of absorbent cotton within the container.

Similar reference characters refer to similar parts throughout the specification and drawings.

I have shown in Figs. 1, 2, and 3 the blanks 25 from which my dispensing container may be made. The blank shown in Fig. 1 generally comprises the body forming portion A, and a cover forming portion B. The body forming portion A comprises rear wall 10, front wall 11 and side 30 walls 12 and 13, all hinged together along the score lines 14. In assembling the container a flap 15 hinged to the rear wall 10 along the score line 14 is cemented or otherwise secured to the free edge of the side wall 13, as shown in Fig. 6 35 of the drawings. Bottom flaps 16 and bottom flaps 17 are hinged respectively to the front wall 11, rear wall 10 and side walls 12 and 13 along the score lines 18. The bottom flaps 16 and 17 are folded inwardly, positioned in superimposed 40 relationship and cemented together to form the bottom wall of the container.

The cover portion B of the container, as shown in Fig. 1, comprises a rear flange 19 hinged to the rear wall of the body portion along the score 45 lines 25. The front flange 20 and the side flanges 21 and 22 are separated from the front and side walls of the body portion by the cut 26. Flanges 19, 20, 21, and 22, and the securing tab 23 are defined from one another by the score lines 24. 50 The top wall flaps 27 of the cover portion are hinged to the rear and front flanges 19 and 20, respectively, along the score line 29 and the top flaps 28 are similarly hinged along the score line 29 of the side flanges 21 and 22. The cover

portion B is assembled by bending the flanges 19, 20, 21, and 22 into tubular form and then gluing or otherwise securing the tab 23 to the free edge of the side flange 22. The top flaps 27 and 28 are then folded inwardly in superimposed relationship and glued together to form the top wall of the cover portion. It is thus seen that a complete container is made from the single blank shown in Fig. 1, the container comprising 10 a body portion A having a bottom wall and enclosing side walls and a cover portion B hinged to the body portion and comprising side flanges and a top wall.

There is shown in Fig. 2 a blank from which 15 the dispensing medium may be made. The dispensing medium comprises enclosing side walls 31 and a securing tab 32, defined from one another by the score line 33. The dispensing medium is provided with a top wall 35 hinged to one of the side walls 31, along the score line 36. The top wall is provided with a dispensing opening comprising a plurality of radially extending slits 37, which define fingers or segments 38 therebetween. Flaps 34 are provided extending 20 from certain of the side walls 31, as shown in Fig. 2 and are defined therefrom by the score lines 36. The dispensing medium is assembled by bending the side walls 31 into tubular form and gluing or otherwise securing the tab 32 to 25 the free edge of one of the side walls. As thus formed, the side walls 31 provide a sleeve adapted to telescope into the body portion A of the container. The flaps 34 are then turned inwardly and the top wall 35 superimposed thereover and glued thereto to form the top wall of the dispensing medium.

A guide device D is provided which is inserted 40 into the dispensing medium to guide the dispensed material through the dispensing opening 40 in the dispensing medium. The guide device D may be formed from the blank shown in Fig. 3 and comprises a bottom wall 41, having a guide opening 44 therein. The side flanges 42 extend from the bottom wall 41 and are defined therefrom by the score lines 43. When the side flanges 45 42 are bent at an angle, they form, in effect, a shallow box, as shown more particularly in Fig. 6.

In packing the container, one end of the absorbent cotton in rope form, as shown more particularly in Fig. 7, is passed through the guide opening 44 from the outside of the bottom wall 41. This same end of the rope is then passed 50 through the sleeve of the dispensing medium and through the dispensing opening in the top wall 35 thereof. The guide device D may then be telescoped into the sleeve of the dispensing medium so that the free edges of the side flanges 42 of the guide device rest against the inside face of the top wall 35 of the dispensing medium, as shown more particularly in Fig. 5. The rope 60 is then coiled within the sleeve of the dispensing medium which is still in inverted position, the coiled material resting on the bottom wall 41 of the guide device. The body portion A is then telescoped over the sleeve of the dispensing medium until the free edge of the dispensing medium comes to rest on the bottom of the body portion. The body portion is then returned to upright 65 position and the container is completely packed and ready for shipment upon the closing of the cover portion B.

It will be noted that the sleeve of the dispensing medium rests, and is supported upon the bottom wall of the body portion of the container. The 75 sleeve is of sufficient height to extend above the

top edge of the body portion so as to provide a seating collar for the cover portion, guiding the cover portion into closing position and frictionally retaining the same in closed position.

When fully packed, the end of the rope R extends above the top wall 35 of the dispensing medium a short distance so as to be easily grasped. This end of the rope R is fully protected against dirt and contamination by the hinged closure B. The plurality of fingers 38, formed by the radiating slits 37 in the dispensing top wall 35, are resilient and may be pulled upwardly by the bottom rope as it is drawn through the dispensing aperture. The resilient fingers 38, however, hold the protruding end of the rope 15 in position and prevent it from slipping out of the dispensing opening and dropping into the container, where it can not be reached. The guiding aperture 44 directs the cotton rope into dispensing position so that the rope moves 20 through the dispensing opening in a vertical direction and prevents binding of the rope against the resilient fingers 38 as it passes through the contracted dispensing aperture.

It is now seen that I have provided a dispensing 25 container formed from paper blanks which can be stamped out by automatic machines now in use. There is very little waste of paper material resulting from the cutting operation in making my container since the blanks are substantially 30 rectangular. The blanks can be folded and assembled entirely on automatic folding and gluing machines without any hand operation whatsoever. The entire container can thus be produced automatically at a fraction of the cost of dispensing 35 containers of this type now in use. It is evident that the dispensing container here shown may be used for dispensing materials other than absorbent cotton and I contemplate using my dispensing container to dispense other materials 40 and other articles of merchandise. The materials packed therein are fully protected from exposure and contamination at all times and the container can be made in any number of attractive shapes and designs to accommodate a variety 45 of uses.

While certain novel features of the invention have been disclosed and are pointed out in the annexed claims, it will be understood that various omissions, substitutions and changes may be 50 made by those skilled in the art without departing from the spirit of the invention.

What is claimed is:

1. A machine made dispensing container comprising a self-supporting set up body portion, a 55 cover portion hinged to the body portion, and a separate dispensing medium formed from a single blank of paperboard material comprising a top wall having a contracted dispensing opening and a sleeve telescoped endwise into the body portion 60 and extending above the top edge thereof to form a seating collar for said cover portion.

2. A machine made dispensing container comprising a self-supporting set up body portion, and a separate dispensing member telescoped 65 endwise into said body portion, said dispensing medium comprising a top wall having a dispensing opening therein and a sleeve seated against the bottom of the body portion and projecting above the top edge thereof, said sleeve containing 70 and enclosing the material to be dispensed.

3. A dispensing container comprising an independent self-supporting body portion, a cover portion hinged to the body portion along one side thereof, and a separate dispensing medium in-

2,015,653

5. inserted endwise into said body portion, said dispensing medium comprising a top wall having a contracted dispensing opening therein and a sleeve resting on the bottom of the body portion and projecting above the top edge thereof to provide a seating collar for said cover portion, said sleeve containing and enclosing the material to be dispensed.

10. 4. A dispensing container comprising a body portion, a dispensing medium comprising a top wall having a contracted dispensing opening therein and a sleeve inserted within said body portion, and a guide device inserted within the sleeve of said dispensing medium, said device being operative to direct the dispensed material through a dispensing opening provided in said dispensing medium.

15. 5. A dispensing container comprising in combination, a self-supporting set up body portion, a dispensing medium including a top wall having a contracted dispensing opening therein and a sleeve inserted endwise into said body portion, said sleeve extending from the bottom of the body portion to a distance outside said body portion, and a cover portion hinged to the body portion, and adapted to telescope over and frictionally engage the outside part of said dispensing medium when the cover is moved into closed position, said sleeve containing and enclosing the material to be dispensed.

20. 6. A dispensing container comprising in combination, a body portion, a cover portion hinged to the body portion along one side thereof, a dispensing medium comprising a top wall having a contracted dispensing opening therein and a sleeve inserted within said body portion, and a guide device inserted within said dispensing medium operative to direct the dispensed material

through a dispensing opening in said dispensing medium.

25. 7. A machine made dispensing container comprising a body portion, a cover portion hinged to the body portion, a separate dispensing medium inserted within said body portion, said dispensing medium comprising a top wall having a dispensing opening therein and a sleeve fitted within the body portion and supporting said top wall in operative position, and a separate guide device 10 telescoped within the sleeve of said dispensing medium and operative to guide the dispensed material through the dispensing opening provided therein.

30. 8. A machine made dispensing container for 15 cotton rope comprising in combination, an independent self-supporting body portion, a cover portion hinged to the body portion, and a separate dispensing medium including a top wall and a sleeve portion formed from a single blank of 20 paperboard material inserted endwise into the body portion and extending above the top edge thereof to form a separate collar for said cover portion, said top wall being provided with a contracted dispensing opening through which the 25 rope is frictionally drawn.

35. 9. A dispensing container for cotton rope comprising in combination, an independent self-supporting body portion, a cover portion hinged to the body portion along one side thereof, a separate dispensing medium including a top wall and a sleeve portion formed from a single blank of 30 paperboard material inserted endwise into said body portion, said top wall being provided with a contracted dispensing opening through which 35 the rope is frictionally drawn.

CHAMPE S. ANDREWS.
